UNITED STATES PATENT OFFICE

EDWARD CHESHIRE, OF MILWAUKEE, WISCONSIN

SHEET FEEDING DEVICE

Application filed August 16, 1924. Serial No. 732,443.

My invention pertains to sheet-feeding devices, and relates especially to devices for feeding sheets to the platen of a platen printing press.

An object of my invention is to provide a feeding device in which the member which carries the sheets is given a movement of a smooth and easy nature, so as to minimize wear and vibration of the parts and to allow of feeding at relatively high speeds without damage to the mechanism or loss of accuracy in its functioning. It is another object to produce a feeding device for platen presses in which there will be a high degree of accessibility both to the feeding device and to the press, and which will permit such operations as the hand-feeding of sheets and the make-ready of the press to be performed with great facility. It is a further object of my invention to produce a feeding device which will be an improvement on others heretofore produced and proposed in simplicity and ruggedness of construction, ease of adjustment and operation, and general efficiency in the performance of its work. And still other and further objects of my invention will appear from the following description and the claims annexed thereto.

I have shown, by way of example, in the accompanying drawings, and described in the following specification, a feeding device constructed in accordance with my invention. It is to be understood however that my invention may be embodied in other forms, and that changes may be made in the form described and shown, without exceeding the scope thereof as defined in the appended claims. As this application relates particularly to means for feeding sheets, the means for delivering the printed sheets from the press described below, and the feed and delivery tables with the automatic means for actuating the same, are not shown in detail, or described at length, herein. Such delivery means, however, is described in my co-pending application, Ser. No. 26,972, filed April 30, 1925.

In the drawings:

Figure 1 is a side elevation of a platen press having a sheet feeding device embody-

ing my invention applied thereto, the feed grippers being in their rear, sheet-receiving position, and the fly-wheel being removed;

Figure 2 is a plan of the same;

Figure 3 is a front view of the same;

Figure 4 is a section on the line 4—4 of Figure 3, looking in the direction of the arrows;

Figure 5 is a section on the line 5—5 of Figure 3, looking in the direction of the arrows;

Figure 6 is an enlarged side view of the feed arm and associated parts, parts being broken away to show the means for effecting the closure of the feed grippers;

Figure 7 is a view similar to Figure 6, but showing a different position of the parts;

Figure 8 is a section on the line 8—8 of Figure 3, showing the mechanism in a position in which the feed grippers are just about to seize a sheet;

Figure 9 is a plan of the parts shown in Figure 8;

Figure 10 is a sectional view similar to Figure 8, but showing the mechanism in a position in which the feed grippers have just deposited a sheet upon the platen;

Figure 11 is a plan of the parts shown in Figure 10;

Figure 12 is a section on the line 12—12 of Figure 10; and

Figure 13 is an enlarged vertical section of one of the feed grippers.

Referring now to the drawings, the main frame of the machine comprises a left-hand side casting 20 and a right-hand side casting 21 which are connected together so as to form a solid framework for the support of the mechanism. Each of these castings is formed with a web which overlies the ordinary front horns *a* of the press, which latter is shown as being of a well-known Gordon type, the horns *a* being those which would ordinarily support the feed-board. Into each of these webs (Fig. 5) are threaded two bushings 22 through which pass studs 23. The studs are formed with collars upon which the lower ends of the bushings 22 rest, and are threaded into the horns *a*. Nuts 24 are provided on the upper ends of the studs 23, and washers are interposed between these nuts

and the webs of the side castings 20 and 21. It will be seen that by this means the castings 20 and 21 are connected securely to the press; and that any slight adjustment of the position of the main frame may be obtained by adjusting the threaded bushings 22 before tightening the nuts 24. Bolted between the side castings 20 and 21 is a ribbed front plate 25 which is disposed so as to be slightly inclined forward from the vertical. The front plate is also bolted between the horns *a* of the press, and serves as a girt to stay the press frame in substitute for parts which are removed in applying the present feeding device. 10 It also forms a guide for the front face of the pile of stock to be fed, as will be later described. A bottom plate 26 is also bolted between the side castings 20 and 21.

To the outside of the right-hand side casting 21 there is bolted a housing 27 (Figs. 3 and 4) formed with bearings 28-28 for a short shaft 29, the bearings being so positioned as to align the shaft 29 with the press shaft *b* which carries the usual bull-wheel *c* 20 connected by the crank-arm *d* with the press-bed *e*. On the inner end of the shaft 29 is secured a cam 30, which is connected (Fig. 4) to the pin which connects the crank arm *d* to the bull-wheel *c*, to which latter the cam 30 stands adjacent. Thus the shaft 29 is caused to rotate with the press-shaft *b*.

A downwardly and forwardly inclined stock-table 31 is located between the side castings 20 and 21, with its front edge adjacent to the front plate 25, and is provided with a stem 32 which has a bearing in the bottom plate 26. Upon this table is placed the pile of sheets to be fed, the front face of the pile engaging the front plate 25, and the side faces being engaged by suitable side guides. Automatic means are provided for elevating the table step by step as sheets are removed therefrom, but are not shown or described herein, as they form no part of the present invention.

45 Extending between the side castings 20 and 21, at a short distance from the front plate 25 is a separator bar 33. This is carried by a pair of arms 34, one of which is pivoted to the left-hand side casting 20. The other arm 50 34 is secured to a shaft 35 having its bearing at one end in the right-hand side casting 21, and at the other end in a member 36 secured to the housing 27 (Figs. 2, 3 and 4). In the drawings, the shaft 35 is shown as formed 55 with an offset portion. This is to provide clearance for other parts of the machine, not shown herein. Near its outer end, the shaft 35 is provided with an arm 37 which is connected by a link 38 with a cam-lever 39 pivoted to the housing 27 and actuated by a cam 40 on the shaft 29.

60 Mounted on the separator bar 33, so as to be adjustable lengthwise thereof, are a pair of pneumatic separator feet 41. These are 65 connected by suitable hose with each other

and with a shut-off cock 42. The cock 42 has a hose connection with a valve 43 (Fig. 4) which also connects with a suitable vacuum pump (not shown). The valve 43 has a stem 44 which engages a cam-arm 45 actuated by a cam 46 on the shaft 29.

As the cam 40 revolves, the separator bar 33 is caused to descend until the feet 41 rest upon the top sheet of the pile of stock. At this time the cam 46 has opened the valve 43, 70 so that suction is applied at the separator feet, whereby the top sheet is caused to adhere to the latter. Shortly afterwards, the cam 40 causes the separator bar 33 to rise again, the top sheet rising with it, adhering to the separator feet 41. The sheet is held in this elevated position until its front edge is seized by the feed grippers to be described below. When the sheet is thus seized, the cam 46 actuates the valve 43, to shut off vacuum 80 from the sheet, thus releasing the latter, to be carried forward to the platen by the feed grippers.

The side castings 20 and 21 are formed with bearings for receiving a rock shaft 47, the end of which extends outwardly of the left-hand side casting 20 and has secured to it the lower end of a feed-arm 48. At its front part, near the top, the feed-arm 48 is formed with a boss 49 in which is cut a slot 50. This slot is curved upon the arc of a circle, the center of which is on the axis of the pin *f* which connects the left-hand crank arm *d* with the bed *e*, in the position which said pin assumes when the bed is in impression position (Fig. 1). Secured in the slot 50 by a nut 51 is a pin 52, to which is rockably connected one end of a link 53. The other end of the link passes through a socket 54 rockably mounted on the pin *f*, and is normally secured against sliding in said socket by means of a latch-pin 55 adapted to enter a suitably placed hole in the link 53. The latch-pin 55 is spring-pressed downwardly so as to be normally maintained in engagement with the hole in 100 the link. Under these conditions the head 56 of the latch pin occupies a correspondingly shaped depression of the socket 54. Upon the latch pin being manually lifted, however, and twisted so that its head cannot enter the depression of the socket 54, it will be maintained in a position out of engagement with the hole in the link 53, the link being then able to slide freely in the socket 54. By this construction, the to and fro rocking of the bed effects a corresponding movement of the feed-arm 48, the latter swinging rearwardly away from the stock pile as the bed rocks rearwardly away from its impression position, and swinging forwardly towards the stock pile as the bed rocks forward to its impression position.

Upon the release of the latch-pin 55, as above described, the feed arm can remain stationary while the press continues its movement.

The feed-arm 48 is formed at its top end with an elongated bearing 57 in which is rockably mounted a gripper-bar 58, the latter being rectangular in cross-section except for the part which enters the bearing 57. The feed grippers 59, two of which are provided, are mounted on the gripper bar 58. Each gripper is formed with a channel-shaped central portion 60 adapted to fit on the square portion of the gripper bar 58, and to be secured against removal therefrom by a plate 61 attached to the bottom of such central portion. A withdrawable spring-pressed pin 62 is mounted in the portion 60 and is adapted to enter one or another of a series of holes formed in the gripper bar 58, thereby to permit the gripper as a whole to be adjusted longitudinally of the gripper bar, to any desired position on the latter. Beyond the central portion 60, the gripper is of channel-shape in cross-section, so as to provide a pair of downward flanges 63, and is formed at its end with a cylindrical guide 64 for receiving the movable gripper-jaw 65, which latter is in the form of a cylindrical plunger adapted to close upon a fixed jaw 66 secured to the guide 64 so as to extend beneath the same. An actuating lever 67 is pivoted between the flanges 63 and is bowed at one end so as to extend over and beyond the central portion 60, at which end it is formed with a notch 68. At its opposite end, the actuating lever enters a recess 69 formed in the movable jaw, this recess being of such length as to permit lost motion between the jaw and the end of the lever. A leaf spring 67^a carried by the gripper presses downward upon the movable jaw 65 with a pressure which may be regulated by manipulating an adjusting screw 67^b.

During the cycle of the machine, by means which will be described below, the lever 67 is moved successively into three effective positions. In the first position, shown in Figs. 8 and 18, it presses upwardly on the top end of the recess 69, thereby raising the movable jaw 65. In this position the gripper is open, ready to receive a sheet. In the second position, it presses downwardly on the bottom end of the recess 69, thereby forcing the movable jaw 65 firmly down on a sheet interposed between it and the fixed jaw 66, whereby the sheet is gripped positively. In the third position, shown in Fig. 10, the movable jaw 65 is pressed by the action of the leaf spring 67^a alone against the sheet interposed between it and the fixed jaw 66, the end of the lever 67 being midway between the ends of the recess 69. In this last position, the sheet is gripped impositively, strongly enough to be moved by the gripper yet lightly enough to escape from the gripper jaws upon its edge coming into engagement with an abutment. If it is desired to modify the strength of the impositive grip-

ping above referred to, this may be effected by manipulating the screw 67^b.

At its end opposite to that which carries the jaws 65 and 66, and beyond the central portion 60, the feed-gripper is formed with a pair of arms 71, in the ends of which are revolvably mounted bushings 72 having square holes therein (Fig. 13). Extending through the square holes of the bushings 72 in the arms 71 of the feed grippers is a rock-shaft 73 of square cross-section for a portion of its length. Upon this rock-shaft are mounted arms 74 having square holes therein, so that they rock with the shaft. These arms 74 are located between the arms 71 of the feed grippers, and engage at their ends in the notches 68 of the jaw-actuating levers 67; so that the rocking of the shaft 73 will effect the several movements of the levers 67. Both the arms 74 and the bushings 72 of the feed-grippers can slide lengthwise of the rock shaft 73, which enables the feed-grippers, carrying with them the arms 74, to be adjusted lengthwise of the gripper bar 58 as units.

Near its end adjacent the feed-arm 48, the rock-shaft 73 has loosely mounted on it an arm 75, the opposite end of which is secured upon an extension 76, of reduced diameter, formed on the end of the gripper bar 58. A link 78 is connected to the rock-shaft 73 and extends downward lengthwise of the feed arm 48. At its lower end, this link enters a guideway on the feed arm and is provided with a cam-roll 79. The cam-roll travels in a cam-slot formed in a floating cam 80 pivoted at 81 to the left-hand side casting 20. As the feed arm swings to and fro the link 78 causes the feed-grippers 59 and the gripper bar 58 to rock in such a manner that the fixed jaws 66 of the feed grippers will follow a certain path with respect to the press platen g. The front part 82 of the cam-slot is so shaped that the jaws 66, during the last part of their forward movement toward the stock pile and the first part of their return movement, will follow a path in which they clear the path followed by the front edge of the platen g as the latter rocks to and from its stationary sheet receiving position. The rear part 83 of the cam-slot is shaped so that the jaws 66 of the feed grippers can follow a path parallel with the face of the platen, and in close proximity thereto, from a point near the center of the platen to a point close to the rear edge of the same.

A shaft 84 extends across the machine and has bearings in the side castings 20 and 21. At one end, this shaft has secured to it an arm 85 which is connected by an adjustable link 86 with a lug extending downward from the floating cam 80. At its other end, the shaft 84 is provided with a cam-arm 87 carrying a roll which engages the edge of the cam 30. The said edge is of such configura-

tion as to cause a drop of the cam-arm 87 when the feed-arm 48 and feed grippers 59 reach the end of their feeding movement. When this drop of the cam-arm 87 takes place, the shaft 84 rocks, and its arm 85, through the link 86, effects a depression of the floating cam 80. This, through the link 78, causes a slight raising movement of the front ends of the feed-grippers, enabling the jaws 66 of the latter, in their return movement, to clear the sheet just fed.

Secured to the end of the rock-shaft 73 is an arm 88 to which is pivoted a link 89, the pivot being located substantially on the axis of the feed-bar 58. The link 89 extends down beside the link 78 and is connected, by a pin 90 with an arm 97 pivoted to the feed arm 48. Upon the pin 90 is mounted a cam-roll 91, which, at one state of the cycle of the machine, is adapted to engage beneath a cam-flange 92 which extends inwardly from the floating cam 80. The cam-flange 92 is so located that it will be engaged by, and remain in engagement with, the roll 91 at and for substantially the same time as the rear part 83 of the cam-slot is engaged by, and remains in engagement with the roll 79. A torsion spring 93 is connected between the arm 75 and a collar secured on the rock shaft 73, and tends to rock the shaft 73 in a clockwise direction, i. e. in a direction in which the arms 74 and actuating levers 67 hold the gripper jaws 65 firmly closed.

As the feed-arm 48 swings towards the platen *g* the cam roll 91 is not at first engaged by anything; consequently the gripper jaws 65 are held firmly closed by the action of the spring 93. When however, near the center of the platen, the feed grippers come close to the platen and begin to move parallel therewith—which is the time the roll 79 enters upon the rear part 83 of its cam slot,—the roll 91 will engage beneath the cam-flange 92, and will thereby be depressed. This depression of the roll 91 and link 89 causes the shaft 73 to rock, against the action of the spring 93, to a sufficient extent to raise the ends of the actuating levers 67 to a position midway in the recesses 69 of the movable gripper jaws 65. When this occurs, the movable jaws 65 will engage upon the fixed jaws 66 by pressure of the leaf springs 67^a only, as has been described above.

Pivoted on the pin 90 which carries the cam roll 91, and resting against a lug 94 on the link 89, is a finger 95 connected by a tension spring 96 with a lug formed on the hub of the arm 97. Formed on the upper part of the floating cam 80, towards the front of the latter, is a cam-lug 98 disposed in a vertical plane somewhat within that occupied by the cam flange 92 of the floating cam 80, the lower face of which lug is inclined downwardly and forwardly. When the feed-arm 48 swings forward to a position where the

feed-gripper jaws are approaching the sheet held suspended from the separator feet 41, the finger 95, the top of which is inclined, engages beneath the cam-lug 98 and is forced downward, carrying with it the link 89. By this means the feed-gripper jaws are fully opened. Just as the feed arm completes its forward movement, the finger 95 passes beyond the cam-lug 98, whereupon the feed gripper jaws close under the action of the spring 93, thus seizing the sheet.

The operation of the feeding device described herein is as follows: Supposing that, so far as press-work is concerned, the press has been made ready for printing, the end-register gage pins *h*, *h* and the side register pin *i* will have been placed in the proper positions on the platen. To adjust the throw of the feed-arm 48 (supposing sheets of a different length have been previously fed) the press is turned over until the bed *e* is in its rearmost, open position, with the pins of the crank-arms *d* on their dead centers. The nut 51 is then loosened and the feed arm 48 moved forward or back (the pin 52 sliding in the curved slot 50) until the jaws 66 of the feed grippers 59 are a very slight distance to the rear of the line which the edge of the paper will occupy when it is in engagement with the end-register pins *h*, *h* (Figures 10 and 11). The pile of stock is placed in the proper position with respect to the location of the side register pin *i* on the platen, and the feed grippers 59 and separator feet 41 are appropriately adjusted on their bars 58 and 33, with respect to each other and with respect to the end-register pins *h*, *h* on the platen. The machine can then be set in motion.

As the feed arm 48 swings forward towards the pile after the roll 91 has left the cam-flange 92, the jaws of the feed grippers are closed; but as soon as the finger 95 strikes the cam-lug 98 they will begin to open. By this time the separator feet 41 will have raised a sheet into position to be embraced by the jaws of the feed-grippers (Figures 8 and 9). As the feed-arm completes its forward movement, the finger 95 passes beyond the cam-lug 98 and the jaws of the feed-grippers snap shut upon the sheet (Figure 6). The valve 43 is then actuated to cut-off the suction and release the sheet from the separator feet 41. Thereupon the feed arm 48 begins to swing rearward, the feed grippers carrying with them the sheet towards the platen *g*, which latter is rocking towards its open position. During the first part of this rearward movement the ends of the feed grippers are considerably above the platen, to allow room for the front edge of the latter to rock past. When, however, the cam-roll 79 reaches the front end of the rear part 83 of the cam-slot, the jaws 66 of the feed grippers will have come into close proximity with

the platen and thereafter will travel parallel therewith. At the same time, the roll 91 will have come into engagement beneath the cam-flange 92, whereby the gripper jaws 65 5 will be relieved from the action of the spring 93 and will engage upon the sheet by the action of the leaf springs 67^a alone, thereby retaining the sheet impositively. Just before the feed arm concludes its rearward 10 movement, the front edge of the sheet strikes the end-register pins *h*, *h*. The feed grippers then proceed onward, slipping off the impositively held sheet and leaving the latter in engagement with the pins. After this, 15 the feed arm moves just the slight distance further necessary to carry the feed gripper jaws clear of the sheet. As the rearward movement of the feed arm 48 is thus completed, the cam causes the shaft 84 to rock 20 slightly, whereby the link 86 swings the floating cam 80 slightly downward. This, through the cam-roll 79 and link 78, causes an upward tilting of the ends of the feed-grippers, allowing them to clear the newly 25 fed sheet in their return movement.

It will be noted that the feed mechanism herein described permits the press to be "make-ready" for a job, and a short run of sheets to be hand-fed, with great facility. 30 All that is necessary is to lift and turn the latch-pin 55, whereupon the feed arm may be manually pulled forward to a position a little in advance of the normal extreme forward position shown in Figure 6. When 35 thus pulled forward, it automatically secures itself by the engagement of an ear 111, with which it is formed, behind a releasable latch 112 pivoted to a lug on the floating cam 80. With the feed-arm thus swung back, the press 40 is fully accessible for "make-ready" from the operator's usual position, and hand-feeding may be performed easily and conveniently.

It will be noted, further, that the feed-arm 45 48 is driven by a crank-motion and has the whole cycle of the press in which to perform its movement. A result of this is that the device may be run at high speeds without loss of feeding accuracy or undue wear of the parts. Moreover the act of depositing the 50 sheet against the end register pins on the platen is performed when the feed grippers are travelling very slowly, having almost reached their dead-center position. This results in great accuracy, and an entire freedom 55 from any tendency of the sheets to bounce back from the register pins when being fed at high speeds. Likewise, the seizing of the sheet from the separator feet is effected when the feed grippers are at their 60 other dead-center position, thus giving plenty of time for this operation to be performed smoothly, and for the vacuum to be cut off from the separator feet 41 before the feed grippers begin to move again.

Having thus fully described my invention,

what I claim as new, and desire to secured by Letters Patent, is:

1. The combination with a press including a bed, a platen and a crank motion device for rocking said bed with respect to said platen, of means for feeding sheets to said press comprising a rockable feed arm, a link connected between said crank motion device and said feed arm for rocking the latter between a sheet receiving position and a position over the platen, a sheet carrying member movably associated with said feed arm, and means for moving said member with respect to said feed arm during the rocking of the latter, whereby said member clears the path traversed by the platen and subsequently comes into proximity with the latter. 70 75 80

2. A sheet feeding device for a platen press, comprising a rockable feed arm, means for rocking said feed arm between a sheet receiving position and a position over the platen, part of the rocking taking place during the movement of the platen, a member movably associated with said feed arm, a sheet carrying device associated with said member, said member being disposed so as to clear the path of the platen during one portion of the movement of said feed arm, and means for moving said member with respect to said feed arm so as to cause said sheet 95 carrying device to travel substantially parallel with the platen during another portion of the movement of said feed arm. 90 95

3. The combination with a platen press including a bed, a platen, and a crank motion 100 device for effecting a rocking movement of the bed with respect to the platen, of means for feeding sheets to said platen, comprising a rockable feed arm, connection means between said feed arm and said crank motion 105 device to cause said feed arm to rock between a sheet receiving position and a position over said platen, a member movably associated with said feed arm, a sheet carrying device associated with said member, said member 110 being disposed so that said sheet carrying device clears the path of the platen during the first part of the movement of said feed arm towards the platen, and means for moving said member with respect to said feed arm, so as to bring said sheet carrying device into 115 proximity with the platen during the latter part of the movement of said feed arm towards the platen.

4. The combination with a platen press including a bed, a platen and a crank motion device for effecting a rocking movement of the bed with respect to the platen, of means for feeding sheets to said platen, comprising a rockable feed arm, connection means between said feed arm and said crank motion device to cause said feed arm to rock between a sheet receiving position and a position over said platen, a member movably associated with said feed arm, a sheet carrying device 120 125 130

associated with said member, said member being disposed so that said sheet carrying device clears the path of the platen during the first part of the movement of said feed arm towards the platen, and means for moving said member with respect to said feed arm, so as to cause said sheet carrying device to travel substantially parallel with the platen during the latter part of the movement of said feed arm towards the platen.

10. 5. The combination with a platen press including a bed, a platen and a crank motion device for effecting a rocking movement of the bed with respect to the platen, of means for feeding sheets to said platen, comprising a rockable feed arm, connection means between said feed arm and said crank motion device to cause said feed arm to rock between a sheet receiving position and a position over said platen, a member movably associated with said feed arm, a sheet carrying device associated with said member, said member being disposed so that said sheet carrying device clears the path of the platen during the first part of the movement of said feed arm towards the platen, means for moving said member with respect to said feed arm, so as to bring said sheet carrying device into proximity with the platen during the latter part of the movement of said feed arm towards the platen, and means for effecting a further movement of said member to separate said sheet carrying device from the platen during the first part of the movement of said feed arm away from the platen.

6. The combination with a platen press including a bed, a platen and a crank motion device for effecting a rocking movement of the bed with respect to the platen, of means for feeding sheets to said platen, comprising a rockable feed arm, connection means between said feed arm and said crank motion device to cause said feed arm to rock between a sheet receiving position and a position over said platen, a member movably associated with said feed arm, a sheet carrying device associated with said member, said member being disposed so that said sheet carrying device clears the path of the platen during the first part of the movement of said feed arm towards the platen, means for moving said member with respect to said feed arm, so as to cause said sheet carrying device to travel substantially parallel with the platen during the latter part of the movement of said feed arm towards the platen, and means for effecting a further movement of said member to separate said sheet carrying device from the platen during the first part of the movement of said feed arm away from the platen.

7. A sheet feeding device for platen presses comprising a movable feed member, a sheet carrying member associated with said feed member and movable with respect thereto,

connection means between the press bed and said feed member for actuating the latter, means for moving said sheet carrying member with respect to said feed member during a portion of the movement of the latter to cause said sheet carrying member to traverse a path substantially parallel with the platen, and means for adjusting said connection means to vary the extent of movement of said feed member towards the platen.

8. The combination with a printing press comprising a bed and a platen adapted to receive an end stop, of means for feeding sheets to said platen, comprising a member movable across the platen towards the end stop thereon to deposit the sheet thereagainst, a link for connecting the press bed with said member, to actuate the latter, and adjustable connection means for an end of said link, whereby the extent of movement of said member towards the end stop can be varied.

9. A sheet feeding device for a platen press, comprising a rockable feed arm, means for rocking said feed arm between a sheet receiving position and a position over the platen, part of the rocking taking place during the movement of the platen, a member movably associated with said feed arm, a sheet carrying device associated with said member, said member being disposed so as to clear the path of the platen during one portion of the movement of said feed arm, means for moving said member with respect to said feed arm so as to bring said sheet carrying device into proximity with the platen at another portion of the movement of said feed arm, and means for adjusting said rocking means so as to vary the extent of movement of said feed arms towards the platen.

10. The combination with a platen press including a bed, a platen and a crank motion device for effecting a rocking movement of the bed with respect to the platen, of means for feeding sheets to said platen, comprising a rockable feed arm, connection means between said feed arm and said crank motion device to cause said feed arm to rock between a sheet receiving position and a position over said platen, a member movably associated with said feed arm, a sheet carrying device associated with said member, said member being disposed so that said sheet carrying device clears the path of the platen during the first part of the movement of said feed arm towards the platen, means for moving said member with respect to said feed arm, so as to bring said sheet carrying device into proximity with the platen during the latter part of the movement of said feed arm towards the platen, and means for adjusting said connection means to vary the extent of movement of said feed arm towards the platen.

11. The combination with a platen press including a bed, a platen and a crank motion

device for effecting a rocking movement of the bed with respect to the platen, of means for feeding sheets to said platen, comprising a rockable feed arm, a link connected between said crank motion device and said feed arm for rocking the latter between a sheet receiving position and a position over said platen, an adjustable connection for an end of said link whereby the extent of movement of said feed arm towards the platen may be varied, a member movably associated with said feed arm, a sheet carrying device associated with said member, said member being disposed so that said sheet carrying device clears the path of the platen during the first part of the movement of said feed arm towards the platen, and means for moving said member with respect to said feed arm, so as to bring said sheet carrying device into proximity with the platen during the latter part of the movement of said feed arm towards the platen.
